DOOR LOCK

Ralph H. Wise, Wayne, Mich., assignor to Ford Motor Company, Dearborn, Mich., a corporation of Delaware

Application October 10, 1950, Serial No. 189,453

4 Claims. (Cl. 292—280)

1

This invention relates generally to a door latch mechanism and particularly to a door latch mechanism of the rotatable bolt and pawl type for use on motor vehicle doors.

An object of the invention is to provide an improved door latch mechanism of the type having a rotatable bolt and a rotatable ratchet controlled by means of a pivotally mounted pawl, the latter being engaged by suitable actuating mechanism to release the ratchet and bolt so that the latter may be rotated to disengage the latch from the associated keeper. The improvement of the present invention resides in the provision of a pawl formed of two pivotally connected sections. One of the sections is pivotally mounted upon a suitable support, and the other section has means thereon for engaging the rotatable ratchet of the latch mechanism to hold the latter in its latched position. In the usual pawl and ratchet construction in locks of this type, a considerable force is exerted by the ratchet against the pawl by reason of the compression of the resilient weather strip around the edges of the door when the door is in its closed position. This pressure, and the resulting friction between the pawl and ratchet, must be overcome by the actuating mechanism to disengage the pawl from the ratchet to unlatch the vehicle door. The articulated two section pawl disclosed in this application facilitates the disengagement of the pawl from the ratchet and makes it possible to readily swing the pawl away from the ratchet regardless of the pressure exerted by the ratchet upon the pawl. In fact, after a slight initial movement of the pawl by the actuating mechanism, the force exerted by the ratchet upon the pawl actually assists in the disengagement.

Other objects and advantages of this invention will be made more apparent as this description proceeds, particularly when considered in connection with the accompanied drawing, wherein:

Figure 1 is a longitudinal vertical cross-sectional view through the rearward portion of a motor vehicle body incorporating the present invention.

Figure 2 is a vertical transverse cross-sectional view taken on the line 2—2 of Figure 1 and showing the latch mechanism in locked position.

Figure 3 is a view similar to Figure 2 but showing the pawl and ratchet in a partially disengaged relationship.

Figure 4 is a view similar to Figures 2 and 3 but showing the pawl completely disengaged from the ratchet.

Figure 5 is a cross-sectional view taken on the line 5—5 of Figure 2.

2

Figure 6 is a cross-sectional view taken on the line 6—6 of Figure 2.

The drawings illustrate the latch mechanism of the present invention as applied to the luggage compartment door of an automobile body, but it will be understood that the device is also applicable to other doors and closure members of motor vehicles as well.

The present invention constitutes an improvement in the construction shown in the co-pending application of Thomas C. Dingman and John W. Jamieson, Serial Number 157,574, and since a considerable portion of the construction of the present invention is the same as that shown in the above co-pending application, reference is made thereto for a more detailed description thereof.

Referring now to the drawings, the reference character 11 indicates the luggage compartment door of an automobile body. The door comprises inner and outer panels 12 and 13 joined together with the inner panel 12 having an outwardly extending lower flange 14. A flexible weather strip 16 is carried by the door at its lower edge and engages the upper flange of a fixed panel 17 extending upwardly from the rearward portion of the floor panel 19 of the luggage compartment.

The latch mechanism is carried by a case 21 having an L-shaped flange 22 secured to the inner door panel 12 by bolts 23 extending through the flange and the panel and engaging screw bosses 24 formed in an L-shaped reinforcing member 26.

A bracket 27 is mounted within the case 21 and forms a partition wall between the front and rear walls of the case. The bracket 27 extends through aligned rectangular openings 28 and 29 in the reinforcing member 26 and the lower flange 14 of the inner door panel respectively.

The latch mechanism is provided with a rotatable toothed latch or rotor 31 having an integral shank 32 extending through the wall 27 with a rotatable toothed ratchet 33 secured to its extended end on the opposite side of the wall 27 from the rotor. The rotor and ratchet thus rotate together as a unit, each being formed with six equally spaced peripheral teeth.

The rotor and ratchet are adapted to be held in latched position by means of an articulated two section pawl or toggle. The lever 36 forms one section of the toggle, and is pivotally mounted upon the partition wall 27 of the case by means of a shoulder stud 37. The wall 27 is formed with boss 38 forming a bearing surface for the ratchet and the toggle linkage. The second section of the toggle linkage comprises

a pawl 39 carried by the lever 36 and pivotally connected thereto by means of a shoulder stud 41. As best seen in Figure 6, the portion of the pawl 39 pivotally connected to the lever 36 is offset from the main body portion of the pawl so that the pawl and the lever generally lie in the same plane adjacent the boss 38 formed on the partition wall 27 of the case. Inasmuch as the opposite end of the shoulder stud 41 is riveted over the rearward side of the lever 36, an elongated slot 42 is formed in the wall 27 to provide clearance therefor.

The lever 36 and the pawl 39 are formed with abutting flanges 43 and 44 respectively limiting relative pivotal movement between the lever and pawl in one direction. The lever and pawl are normally held in this limiting position by means of a spiral spring 46 having its inner end seated in a slot formed in the head of the shoulder rivet 41 non-rotatably carried by the pawl 39, and having its outer end engaging a flange 47 struck upwardly from the pawl 39. It will thus be seen that while the lever 36 and pawl 39 forming the two sections of the toggle linkage are normally held in their extended position by the spring 46, the toggle may be collapsed against the force of the spring.

The pawl 39 is formed with a projection 48 engageable with the teeth of the ratchet 33 to hold the latter against clockwise rotation. Referring particularly to Figure 2, it will be seen that in the latched position of the mechanism, the pivotal axis 41 between the lever 36 and pawl 39 is located slightly below a line 50 extending from the axis 37 of the pivotal connection between the lever 36 and the supporting wall 27 and the effective point of contact between the projection 48 of the pawl 39 and the adjacent tooth of the ratchet 33. The effective point of contact is of course the outermost point of the ratchet tooth engaging the pawl. The slightly over-center relationship of the two sections of the toggle linkage is effective to maintain the latter extended and to hold the ratchet in its latched position until released by a separate actuating force. It will be noted that a spiral spring 51, having its inner end seated in the slotted head of the shoulder rivet 37 non-rotatably mounted upon the supporting wall 27, and its outer end engaging a flange 52 struck upwardly from the lever 36, continually urges the lever 36 and the pawl 39 engaged thereby in a counterclockwise direction toward its latched position.

In the illustrated embodiment of the invention the rotor 31 is adapted to be engaged by a keeper 59. As shown in Figure 1, the keeper 59 is secured by bolts 61 to a fixed bracket 62 welded to the stationary body structure. Referring now to Figure 2, the upper portion of the keeper 59 is formed with a toothed projection 63 adapted to engage the rotor 31 between adjacent teeth thereof. The edge of the keeper opposite the toothed projection 63 slidably engages a fixed cam 64 rigidly mounted within the case 21. It will be apparent that the closing movement of the luggage compartment door 11 causes the projection 63 on the keeper to engage the rotor and rotate the latter in a counterclockwise direction as seen in Figure 2 until the latched position is reached, and conversely, the opening movement of the door is accompanied by a clockwise rotation of the rotor to free the latter from the keeper.

The lever 36 is formed with an upwardly and

rearwardly bent arm 53 projecting into the path of the lower arm 54 of a bell crank lever pivotally mounted upon the upper portion of the supporting wall 27 by means of a rivet 56. The upper arm 57 of the bell crank lever is detachably connected to a link 58 connected to a suitable actuating mechanism (not shown) such as a door handle or other operating device. Upward movement of the link 58 by the actuating mechanism swings the bell crank lever in a counterclockwise direction and through its contact with the arm 53 of the lever 36 rotates the latter in a clockwise direction against the action of the spring 51. When the luggage compartment door 11 is closed, the weather strip 16 between the periphery of the door and the adjacent body structure is compressed and exerts a force tending to open the door. This results in a force being exerted by the ratchet teeth upon the projection 48 of the pawl 39, and the resulting friction resists swinging movement of the pawl away from the ratchet. The toggle formed by the pivotally connected lever 36 and pawl 39, however, is resiliently held in extended position only by the spiral spring 46, and initial actuation of the lever 36 by the bell crank lever 57 causes the toggle to break and to move to the position shown in Figure 3. It will be seen that in this position the abutting flanges 43 and 44 of the lever 36 and pawl 39 respectively have separated and the relative pivotal movement between the lever and pawl has resulted in moving the axis 41 of the pivotal connection therebetween to a position above the line 50 connecting the pivotal axis 37 with the effective point of contact between the ratchet tooth and the pawl.

The actuation of the bell crank lever 57 by the actuating mechanism to swing the lever 36 from the position shown in Figure 3 to that shown in Figure 4 is effective to completely disengage the pawl 39 from the ratchet 33. During this phase of the disengaging movement of the latch mechanism the force of the ratchet 33 upon the projection 48 of the pawl 39 actually assists in collapsing the toggle since the pivotal axis 41 between the two sections of the toggle linkage is above the center line 50. Consequently, only a very moderate force need be exerted by the actuating mechanism to unlatch the door lock. This is extremely advantageous with door locks employing actuating mechanism of the push button type or the key release type in which only a limited amount of actuating force can be applied conveniently.

The pawl 39 is provided with a tongue 66 extending beyond the toothed projection 48. The extreme end of the tongue 66 slides between the supporting wall 27 of the case and a flange 67 bent downwardly from the upper portion of the case to provide a guideway therebetween. The pawl 39 is thus held against inadvertent displacement. The tongue 66 extends over the adjacent tooth on the ratchet 33 and positively prevents movement of the pawl 39 beneath the position shown in Figure 2, thus insuring the proper return of the pawl to latching position with the ratchet when the actuating mechanism is released and preventing the pawl 39 from being carried around with the ratchet when the toggle formed by the pawl and the lever 36 is collapsed.

It will be seen that the construction described above provides a simple yet effective latching device adapted to be unlatched with a minimum of effort, and applicable to locked mechanisms

of various types for vehicle doors, luggage compartment lids and so forth.

It will be understood that the invention is not to be limited to the exact construction shown and described, but that various changes and modifications may be made without departing from the spirit and scope of the invention, as defined in the appended claims.

What is claimed is:

1. In a latch mechanism for a motor vehicle door, a support, a toothed latching device rotatably mounted upon said support, a lever member pivotally mounted upon said support adjacent said toothed latching device, a pawl member pivotally supported upon said lever member and having an integral portion directly engageable with the teeth of said toothed latching device to hold the latter in latching position, cooperating stop means on each of said members limiting pivotal movement between said members in one direction, spring means supported upon one of said members and engaging the other of said members to yieldably hold said members in said limited position, additional spring means urging said pawl member toward said toothed latching device, and actuating means engaging said lever member to rotate the latter about its pivotal connection with said support to swing the pawl member carried thereby away from said toothed latching device, said first-mentioned spring means holding said lever and pawl member together for normal rotation as a unit but permitting relative pivotal movement between said members if the resistance to rotation of said members as a unit exceeds a predetermined amount.

2. In a latch mechanism for a motor vehicle door, a support, a toothed ratchet pivotally mounted upon said support, an articulated toggle linkage for selectively holding said ratchet against rotation in one direction, said toggle linkage including a link pivotally mounted on said support and a second link pivotally mounted upon and wholly supported by said first link, said second link having an integral projection thereon directly engageable with said toothed

ratchet, stop means determining the extended relationship of said toggle links, yieldable means operable upon said toggle linkage to urge said projection toward latching engagement with said ratchet, and actuating means for rotating one of said links about its axis to disengage said projection from said ratchet.

3. The structure defined by claim 2 which is further characterized in that the pivotal axis between said links is slightly offset in the latched position of said mechanism from the line extending between the pivotal connection of said first link to said support and the effective point of contact between the projection on said second link and the adjacent tooth of said ratchet.

4. The structure defined by claim 2 which is further characterized in that the pivotal axis between said links is slightly offset in the latched position of said mechanism from the line extending between the pivotal connection of said first link to said support and the effective point of contact between the projection on said second link and the adjacent tooth of said ratchet, said actuating means being engageable with said first link and effective upon operation to rotate the latter about its pivotal connection with said support and to swing the pivotal connection between said links to the opposite side of said line to enable said toggle linkage to collapse from its extended position to facilitate the unlatching of said mechanism.
